(57) **CLAIM**

The ornamental design for a motorized scooter, as shown and described.

DESCRIPTION

FIG. 1 is a top, front, and left side perspective view of a motorized scooter showing our new design;

FIG. 2 is a top, rear, and right side perspective view thereof;

FIG. 3 is a bottom, front, and left side perspective view thereof;

FIG. 4 is a bottom, front, and right side perspective view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is a top plan view thereof; and,

FIG. 10 is a bottom plan view thereof.

1 Claim, 9 Drawing Sheets# US D832,150 S
